UNITED STATES PATENT OFFICE.

NOAH S. WOOD, OF ROACHDALE, INDIANA.

DESIGN FOR A CABINET.

SPECIFICATION forming part of Design No. 22,648, dated July 25, 1893.

Application filed June 23, 1893. Serial No. 478,661. Term of patent 14 years.

To all whom it may concern:

Be it known that I, NOAH S. WOOD, a citizen of the United States, residing at Roachdale, in the county of Putnam and State of Indiana, have invented a new and original Design for Cabinets, of which the following is a specification.

The invention relates to a new and original design for cabinets.

10 The object of the present invention is to provide an ornamental and attractive cabinet; and the essential feature resides in a cabinet having a rectangular lower portion, and provided with an upper portion approximately

15 T-shaped in plan view with angularly arranged front faces and triangular side spaces.

In the drawings—Figure 1 is a perspective view of a cabinet showing my original design. Fig. 2 is a plan view of the same.

20 Referring to the drawings, 1 designates a cabinet having upper and lower portions 2 and 3. The lower portion is rectangular; and the upper portion is T-shaped in plan view with front and lateral extensions 4 and 5.

The lower rectangular portion 3 of the cabinet has drawers and compartments; and the upper portion is provided with a cover and drawers. The front and lateral extensions 4 and 5 of the upper portion of the cabinet form, at the sides of the cabinet, triangular spaces 30 6, in which are arranged triangular shelves 7; and the front extension has front faces 8 arranged at an angle to one another and forming a polygonal front to the upper portion of the cabinet. It will be apparent that 35 the cabinet presents an ornamental and attractive appearance.

What I claim is—

The design for a cabinet herein shown and described.

40 In testimony that I claim the foregoing as my own I have hereto affixed my signature in the presence of two witnesses.

NOAH S. WOOD.
